FIG. 1

FIG. 2

FIGURE 1 is a top, front and left side perspective view of a flat duplicator, showing my new design; and FIGURE 2 is a bottom view thereof.

The right side, not shown, is substantially symmetrical with the left side view, and the back is a flat, unornamented surface. The top stencil frame is swingably pivoted to the bed portion below the sides of the bottle wells.

I claim:

The ornamental design for a flat duplicator, substantially as shown and described.
